ALLAN RAMSEY, OF CHICAGO, ILLINOIS, ASSIGNOR, BY MESNE ASSIGNMENTS, TO SCHWEITZER & CONRAD, INC., OF CHICAGO, ILLINOIS, A CORPORATION OF DELAWARE

DISCONNECTING SWITCH

Application filed May 31, 1927. Serial No. 195,170.

This invention relates to electric switches, particularly to disconnecting or air break switches, and its object is the provision of a generally improved, simplified, inexpensive and rugged construction that may be readily and positively opened regardless of adverse influences tending to hold it closed and in which positive closing and good contact is assured.

The present invention provides generally improved means for imparting a relatively great or powerful initial or preliminary breaking or opening force, which means is characterized by its simplicity and ruggedness, and by the absence of additional joints or the like in the swinging blade member.

The invention avoids any difficulties encountered, as well as the necessity for any additional joint protecting precautions where the blade member is provided with a pivoted joint in addition to its swingable mounting for the purpose of securing a compound swinging action.

The invention also provides for imparting a relatively great or powerful closing force and for securing good contact.

The advantages of such provisions as these in switches of the disconnecting type will be apparent at once to those skilled in the art.

It is to be understood, however, that the present invention is not limited to a particular use or purpose, and that by providing the switch with suitable arcing horns, for example, it will be suitable for interrupting actual load in substantially the manner in which other air break switches are employed.

In a particular embodiment of the present invention, I employ a movable contact or clip member with the movable arm or blade member, catching the movable contact with the movable arm or blade member in its closing movement and then bringing the two parts endwise into engagement. Each part requires only a simple movement, as distinguished from a compound jointed action, and a positive closing action of relatively great force is provided with a relatively powerful endwise sliding engagement between the movable arm or blade and contact members.

The clip or contact member tends to swing

into open position under the influence of a suitable spring and in operating the switch from closed to open position the blade and clip or contact members swing together until the blade is withdrawn from the clip, at 55 which point the blade or switch member leaves the clip and moves independently to full open position. After the blade or switch member leaves the clip, the clip may move a few degrees further under the influence of 60 the spring, this extra movement of the clip or contact member guarding against the blade or switch member not making proper entry into the clip member when the switch is closed.

In operating the switch from open to closed position, the blade or switch member is swung in the opposite direction until the blade member engages or enters the clip, whereupon, it picks up the clip member and 70 swings it with the blade, bringing the clip and blade members endwise into engagement with a relatively great or powerful force through the endwise components of the closing angular movements of the clip and blade members. This action slides the blade and 75 clip or contact members positively into good contact.

The clip or contact member may be housed against the weather and particularly against 80 sleet and ice accumulations, by a suitable hood or housing which may operate not only to protect the clip or contact member, but also to cover and protect the adjacent end of the blade or switch member when the same is in 85 engagement with the clip or contact member.

The present invention also provides an improved form of clip or contact member.

In order to acquaint those skilled in the art with the manner of constructing and 90 operating the present invention, I shall now describe the particular embodiments of the invention selected for illustration in the accompanying drawings, in which

Fig. 1 is a front elevational view of a 95 switch embodying the present invention;

Fig. 2 is a side elevational view of the same;

Fig. 3 is a detail longitudinal section 100 through the clip or contact member taken

on the line 3—3 of Fig. 1 and showing the mounting therefor, and one form of spring arrangement for swinging the clip or contact member to the position shown in dotted lines in Fig. 1;

Fig. 4 is a detail section taken on the line 4—4 of Fig. 3 transversely across the axis of swinging movement of the clip or contact member;

Fig. 5 is a transverse detailed section through the free end of the clip or contact member and through the protective hood on the line 5—5 of Fig. 3;

Fig. 6 is a detail longitudinal section, partially in elevation and taken on the line 6—6 of Fig. 3; and

Fig. 7 is a fragmentary front elevational view of the contact or clip end of another embodiment of the invention.

The switch of the present invention is adapted for one, two or three pole gang operation or for any other suitable or preferred group arrangement.

Referring first to the embodiment of the invention illustrated in Figs. 1 to 6, 5 designates the relatively stationary insulator upon the outer end of which the contact or clip member of the unit is mounted and 6 designates the rotatable or rocking insulator upon the outer end of which the blade member is suitably attached to turn with the insulator 6. The clip or contact member is pivoted on the outer end of the stationary insulator 5.

The insulators 5 and 6 may be of any suitable or preferred form. The insulator 5 is shown as mounted on a post support 8 having an enlarged flanged end 9 fixedly mounted upon a suitable base 10. Rigidly secured upon the outer end of the insulator 5 is a fitting 12 which may be in the form of a cap or fitting, and rigidly secured to the outer end of the insulator cap 12 at 13, is a bearing member 14, as shown in Fig. 3. The bearing member 14 has a lateral arm 15 and secured in the bearing member co-axially with the insulator 5 as by means of a pin 16 passing diametrically therethrough, and through an integral hub 17 on the bearing member 14 is a post 18 upon which the contact or clip member 20 is rotatably journaled. The surface of the bearing member 14 adjacent the cap member 12 may be relieved centrally at 19.

The contact or clip member comprises a pair of similar ribbon-like clips or plate members 20, 20, which may be of bus copper or other suitable material. The clip members 20, 20 have registering apertures 21 through which the pivot post 18 loosely passes and the ends of the clips 20 which cooperate with the switch arm or blade member are spread at 22 and re-curved inwardly at 23, rounded at 24 to guide the switch arm or blade member properly therebetween and with their free ends terminating at 25 (Fig. 3). The re-curved ends of the clips 20 may be pro-

vided with longitudinal cuts 26 (Fig. 6) for increasing the springiness of the contacting ends of the clips, which, due to their formation and inherent resiliency, are adapted to yieldingly receive the switch arm or blade member 28 between them and the inturned ends of the clips are pressed yieldingly and into firm and good contact with the adjacent end of the blade member over the entire contacting portions thereof.

Adjacent the pivot post 18 the clip members 20 are secured by cap screws 29 to the closed outer or upper side 30 of a spring housing 32, the opposite side of which is open at 33. The opposite ends 34 of the clips 20 extend from the opposite side of the pivot 18 and suitable flexible conductor means 35, which may be in the form of suitable copper braid, are connected between and transmit the current from the relatively stationary terminal to the swingable clips 20.

The conductor means 35 is shown as clamped at one end between the clip members 20 by suitable nuts and bolts 37, and at its opposite end between the lateral arm 15 and a terminal plate 38 by nuts and bolts 39. A suitable socketed terminal member 40 is secured to the terminal plate 38 and one of the line wires or conductors 42 is suitably connected with the terminal member 40.

The spring housing 32 is rotatable upon the pivot post 18 with its open side presented toward and closed by the bearing member 14 and preferably with clearance therebetween, as shown, the bearing member 14 completing the enclosure of the spring 48. The housing 32 has an outwardly arched strap 44 through which the outer end of the post 18 passes and has threaded engagement with a nut 45 which may be threaded up into engagement with the strap 44 to secure the housing 32 in place upon the post 18 without binding the clips or other parts carried by the rotatable housing.

Within the housing 32 is a spiral spring 48 having one end anchored at 49 (Fig. 4) to the stationary post 18 and its opposite end turned at 50 over a shoulder or internal lug 52 on the housing 32, the expansion tendency of the spring 50 tending to turn the housing 32 and clip members and other parts carried thereby in a clockwise direction as viewed in Fig. 4. The housing 32 has an external lug 54 adapted to engage a fixed stop 55 (Fig. 4) to limit the turning of the housing 32 in a clockwise direction, as viewed in Fig. 4, in which direction the clip members 20 are swung to open position. Engagement of the lug 54 with the fixed stop 55 limits the opening movement of the clip members under the influence of the spring 48.

The housing 32 is also provided with a lug or abutment 54' which engages the stop 55 and limits the closing movement of the clip, that is, the engagement of the lug 54' with

the stop 55 limits the rocking or turning movement in the opposite direction.

For the purpose of protecting the contact ends of the clip members 20 and the adjacent contact end of the switch or blade member 28 upon cooperation or engagement of the same therewith, the clip or contact members 20 are provided with a housing or hood 60 comprising a pair of similar and complementary housing parts 62 dished to surround and enclose the re-curved contact ends of the clips 20 and having abutting marginal flanges 63 (Fig. 2). The housing members 62 have extensions 64 at the closed end of the housing and these extensions are clamped by bolts 65 to the clip members 20. At the opposite end the housing 60 has an opening 68 extending substantially entirely across the same and of a width greater than the width 20 of the blade member 28 to receive the end of the blade member and accommodate the closing and opening action which occurs. This greater dimension of the opening 68 is shown in Fig. 6, and in the opposite direction this opening 68 is, as shown in Fig. 3, preferably dimensioned to just receive the thickness of the blade member 28 and to guide the blade member properly between the re-curved free ends 23 of the clip members 20. Flared diagonally from the edges defining the lesser dimension of the opening 68, as shown in Fig. 3, are flanges 70 defining a flared guide mouth for receiving and guiding the end of the switch or blade member 28 into the clip housing and between the clip members 20. The ends of the housing members 62 may be clamped together at opposite sides of the opening 68 by bolts 72 between and from which the blade member 28 passes into and from engagement with the clip members 20.

Suitable spring clips 75 may be clamped by bolt and nut means 76 (Fig. 3) with their free ends spread at 77 over the free ends 25 of the clips 20, tending to yieldingly close these clips upon the blade member 28.

The switch or blade arm or member 28 may be formed of a bar of bus copper or other suitable material suitably dimensioned and 50 with the edge which is presented to and engages the clip and hood in closing beveled into one end at 78, as shown in Fig. 6.

The blade member 28 may be suitably trussed at 79, for strength, suitable spacers 80 being provided and the mounted end of the blade being rigidly attached by bolts 81 to a suitable cap fitting 82 rigidly mounted upon the outer end of the insulator 6 to turn or rock therewith. The other line conductor 83, the circuit between which and the conductor 42 the unit disclosed is adapted for opening and closing, is connected to a socketed terminal 84 which may be, in turn, connected through a terminal 85, and suitable

flexible conductor means 86 to the rocking end of the blade member 28.

The insulator 6 is shown as mounted upon a rotatable or rocking post 87 which passes through the base 10 and is journaled for 70 rocking movement in a suitable journal or bearing 88.

The rocking insulator 6 or post 87 therefore has an arm 89 (Figs. 1 and 2) suitably secured at 90 to turn or rock the insulator 6 75 therewith. The arm 89 is pivotally connected at 91 with a link 92, which link 92 may connect through suitable bell crank arms and links to a pivoted operating lever for remote control, that is, for opening and closing the 80 switch from the bottom of the pole or tower where the switch is so arranged. It is to be understood that the link 92 may be similarly connected with similar arms 89 upon adjacent switches by which a gang or group of two or 85 three, or even more, switch units of this sort may be operated in unison. Three switch units so connected are particularly adapted for opening and closing a three-phase circuit, 90 as well understood in the art.

With the parts in closed position, as shown in full lines in Fig. 1, in operating the switch from closed to open position, the rocking insulator 6 is turned by means of the arm 89 and connecting link 92 from the operating 95 means (not shown), turning or swinging the blade 28 with it toward the dotted line position at B in Fig. 1. The swingable clip means swings with the blade about the pivot 18 toward the dotted line position A in Fig. 1, the blade member and clip or contact means moving together until the blade is withdrawn from the clip means and hood, at which point the blade leaves the clip and may swing independently to a position 90 degrees from its starting point, as shown in dotted lines at 100 B in Fig. 1. After the blade leaves the clip and hood, the clip may swing a few degrees further to the left under the influence of the spiral spring 48 and until the lug 54 engages the stop 55, this extra movement guarding 105 against the blade not making proper entry into the clip housing when the switch is closed.

In operating the switch from open to closed position, the rocking or rotatable insulator and blade are turned in the opposite direction or to the right (Fig. 1) until the beveled tip 78 of the blade member 28 enters the mouth of the opening 68, whereupon, 110 the swingable contact or terminal clip is caught or picked up by the end of the blade member and rotates with the blade member about its pivot 18 until the clip means and blade member are brought into line in closed position, as shown in full lines. It will be apparent that as the blade catches the clip means in its closing movement and swings the same therewith, the clip means and blade member are brought endwise into engage- 115 120 125 130

ment. The sliding engagement between the clip members and the cooperating end of the blade member provides a wiping, self-cleaning contact, and relatively perfect engagement between the contact members and blade member is assured. The endwise movement of the contact and blade members into engagement is the vertical component of the swinging or angular movement of the contact and blade members about the axis of the pivot 18 and the axis of the rotatable insulator 6, respectively, which gives a relatively great or powerful closing force for positively closing the switch regardless of adverse influences tending to oppose such closing.

Similarly, in opening the switch, the endwise separation of the contact and blade members is the vertical component of movement of the angular movement of the contact and blade members, giving a powerful breaking force for positively breaking any bind in the engagement of the blade and contact members due to static friction, corrosion, ice or sleet accumulations or other cause.

This is particularly advantageous in disconnecting switches which are frequently large and heavy and frequently have considerable friction and inertia and which are used a great deal in out-door substation equipment installations where they are subject to the weather and particularly to ice and sleet accumulations and which are frequently not operated for long periods of time. Switches of this sort frequently carry considerable current and particularly relatively high tension current. They are adapted for dividing transmission lines into sections to facilitate inspection and repairs and are commonly placed in circuit with circuit breakers and other apparatus for use in isolating the apparatus with which they are associated to permit working thereon with safety.

The spring means 48 moves the clip or contact means to the open dotted line position A (Fig. 1) and this contact or clip means is moved to closed position by the co-operation of the blade member 28 therewith and against the tension of the spring means 48. The blade member 28 may be limited in its closing movement in any suitable manner to position the parts as shown in full lines in Fig. 1, as well understood in the art, and the opening movement of the blade member 28 may also be limited in any suitable or preferred manner.

In the embodiment of the invention shown in Fig. 7, the same action is employed, but instead of having a housed contact or clip, the contact or clip means is open and the movable switch member or arm 28' has a pair of fingers 95 and 96 which compel meshing of the cooperating contact means of the switch in substantially the same manner.

The contact or clip means 20' is pivoted at 18' upon the outer end of the stationary or relatively fixed insulator 5', as before, but instead of the housed spiral spring for throwing the contact or clip means 20' in the direction of the arrow C (Fig. 7) about the pivot 18', a spring 48' is employed. This spring 48' is shown as secured at 97 to the insulator cap or fitting 12' and at 98 to the contact or clip means 20' and tends to swing or urge the contact or clip means 20' in the direction of the arrow C about the pivot 18'. The free ends of the arms 95 and 96 may be provided with suitable rollers 100 and 102.

As before, in operating the switch from closed to open position, the blade member and clip means 20' swing together until the blade member is withdrawn from the clip means and the clip may be moved a few degrees further to the left to guard against the blade not making proper entry into the clip when the switch is closed. The swing of the contact or clip means in the direction of the arrow C, as well as in the opposite direction, may be limited by suitable stop means, as before.

In operating the switch from open to closed position, the blade member is swung toward closed position until the arm 95 picks up the clip 20' and rotates it with the blade until the clip and blade are brought into line. The opening and closing forces are, as before, the lineal components of the angular movement of the clip means 20' and switch member 28', providing relatively powerful opening and closing forces to assure proper closing and positive opening, regardless of adverse influences. In closing the embodiment of Fig. 7, the contact or clip means 20' and the cooperating end of the blade member 28' are guided endwise into contacting engagement by the rollers or outer ends of the arms 95 and 96.

The spring clips 75 (Fig. 3) are shown as clamped between the contact members 20, 20'. The bolts 72 (Figs. 3 and 6) may be provided with suitable spacers between which the switch arm enters into engagement with the clip or contact member.

I claim:—

In combination, a pair of clip members having their contact engaging ends spread and re-curved inwardly, registering openings in said clip members for receiving a pivot pin, a protecting hood mounted upon said clip members and covering the spread ends thereof, and a flared mouth on said hood for directing a cooperating switch arm into position between the re-curved ends of said clip members.

In witness whereof, I hereunto subscribe my name this 26th day of May, 1927.

ALLAN RAMSEY.
